CARTON OR CONTAINER

William A. Ringler, Wayne, Pa., assignor to National Folding Box Company, New Haven, Conn., a corporation of New Jersey

Application February 7, 1942, Serial No. 429,846

12 Claims. (Cl. 229—7)

The present invention relates to cartons or containers which may be reduced in size during use.

More specifically the invention pertains to improvements in cartons or containers constructed to be reduced in size and corresponding capacity, preferably by simple tearing or other severing, each carton or container having an outer slideable shell, or equivalent cooperating part, and closure flaps for jointly effecting the closure of the dispensing opening of the carton or container and maintaining the slide shell in secured position relative to the body of the carton or container.

In the more preferred embodiments of the invention, the dispensing opening of the body is disposed at one end, usually held or placed in upward position and the closure flaps are integral or otherwise secured to the material of the carton or container to project into and to be moved within the zone of such dispensing opening.

Advantageously the body of the carton or container has a closure flap integral therewith or otherwise secured thereto, cooperating with closure flaps of the slideable outer shell, for attaining the objects of the invention.

Embodiments of the invention are preferably in the form of folded boxes manufactured from flexibly resilient sheet material, such as cardboard or other suitable paper stock or like material.

It is desirable to dimension the outer or slide shell to provide for a fairly snug fit with the walls of the body part of the carton or container, for preventing unintended movement of the shell relative to the body part. Embodiments of the invention may comprise means for fixedly positioning the outer or slide shell relative to the body part, which positioning means is supplemental to the closure flaps and whereby the outer or slide shell may be fixedly positioned when the closure flaps are in open position.

Further features and objects of the invention will be more fully understood from the following detail description and the accompanying drawings, in which

Fig. 1 is a perspective view of a carton or container, illustrating a preferred embodiment of the invention, in full size, shown in open position. Fig. 2 is a side elevation of the embodiment of Fig. 1 illustrating the relative movements of the respective parts of the carton or container preparatory to reducing the size of the carton or container. Fig. 3 is a detail perspective view of the upper portion of the carton or container of Fig. 1 indicating the application of a revenue stamp or other sealing medium for sealing the carton or container prior to the stage of dispensing its contents. Fig. 4 is a longitudinal central sectional view of Fig. 1. Fig. 5 is a longitudinal sectional view of the carton or container when reduced in size, the cover flap being shown in closed position. Fig. 6 is a perspective view of

Fig. 5, showing the cover flap in open position. Fig. 7 is a perspective view of another embodiment of the invention. Fig. 8 is a longitudinal central sectional view of Fig. 7. Fig. 9 is a plan view of Fig. 7. Fig. 9 is a plan view of a form of blank of the body part of the embodiment of Figs. 7 and 8.

Fig. 10 is a perspective view of another embodiment of the invention, illustrating the same in full size and the closure flaps in open position. Fig. 11 is a perspective view of the embodiment of Fig. 10 illustrating the same. Fig. 12 is a detail enlarged sectional view on line 12—12 of Fig. 10. Fig. 13 is a plan view of a typical blank for forming the outer shell of the embodiments shown in Figs. 10, 11 and 12. Fig. 14 is a plan view of a typical blank for forming the body part of the embodiment shown in Figs. 10, 11 and 12.

Referring to the embodiment shown in Figs. 1 through 6, the same comprises the body part 20 adapted to be charged with the contents to be dispensed, an outer shell 21 telescopically and slidably related to the body part 20, and the coacting closure flaps, designated generally 22, for jointly closing the dispensing opening of the body part 20 and for retaining the outer shell 21 in secured relation with respect to the body part 20.

As one form of such coacting closure flaps 22, there is provided in the stated embodiment the main closure flap 22a, hingedly secured to the outer shell 21, the oppositely related secondary flaps 22b, 22b, also hingedly secured to the sliding shell 21, with which is combined the flap 22c, hingedly secured to the upper portion of the body part 20. The flap 22c is shown extending generally in like direction as the main closure flap 22a. Accordingly, when the stated coacting closure flaps are moved to closing position as is illustrated in Fig. 4, the contents of the body part 20 are protected from exterior dust or other foreign substances and interiorly generally sealed against sifting of contents and loss of flavor and/or odor imparting constituents, moisture and the like, as well as thereby securing the outer shell 21 in fixed closed position relative to the body part 20.

The carton or container illustrated in Figs. 1 and 4 is particularly adapted for tobacco such as smoking and other forms of tobacco products, indicated 23. Desirably, and as is the custom for tobacco products, such contents 23 are per se enclosed in a wrapper usually of paper or like sheet material, thus enhancing the preservation of aroma and flavor imparting constituents of the contents. Also, pursuant to the practice required under the excise revenue laws of the United States and other countries, the package is required to be sealed as by revenue stamp, indicated at 24, see Fig. 3, which serves also to hold the closure flaps 22 in secured closed position as well as protection against loss of contents in ship-

ment, against tampering of contents, etc., and also necessitating the tearing of the stamp or other sealing medium to gain access to the contents.

A feature of the embodiment shown in Figs. 1 through 6 is the capability of the carton or container to be reduced in size, especially desirable at one or more successive stages as the contents are dispensed. The embodiment shown in Figs. 1 through 6 illustrates a reduction to half size, as typical of reduction in size generally. To such end, the material of the body part 20 is locally weakened to facilitate severing, as by providing one or more score lines 20a, shown for illustration as formed of serially spaced dot-and-dash lines of scoring which extend uniformly about the complete periphery of the body part 20, in this instance centrally transversely thereof. When it is desired to reduce the body part 20 to such half or other partial size, the closure flaps 22 are moved to open position and the slide shell 21 is moved downwardly relative to the body part 20 to thereby expose the severing score line 20a whereupon the upper portion of the body part 20 may be readily severed thereat, thus reducing the body part to its halved or other reduced size. Such reduced size is illustrated in Fig. 6, wherein the closure flaps 22a and 22b are shown in open position; these closure flaps may then be moved to closed position, as is shown in longitudinal central section in Fig. 5, to afford placing the same in a pocket of a garment or the like of the user or in other suitable place of storage, and thus protected against dust or other foreign material and generally also against loss of contents, etc.

The body part 20 per se may be formed pursuant to conventional practice to provide the same with the flap 22c and its closeable bottom 20b, through which the contents of the body part may be charged in the original packaging of the carton or container.

As indicated in the drawings the terminal portions of the flaps 22a and 22c are tapered, arcuately tapered as shown, to facilitate entry, when closing, within the clearance between the pertinent ends of the outer slide 21 and the body part 20, in the instance where the body part is of full size. When the upper part of the body part is severed, the flap 22c is also removed from the assembly, as appears from Figs. 5 and 6, the closure flaps 22a and lateral closure flaps 22b, 22b, however, cooperating to close the dispensing opening of the body part.

When smoking tobacco or other contents are per se originally enclosed in a separate wrapper, a common practice when the contents are charged by employment of a conventional packaging machine of the weight packaging type, the operation of dispensing such contents from stage to stage results in expanding the contents remaining in the lower portion, of the body part and such expansion assists in increasing the friction between the walls of the outer shell 21 and the walls of the remaining portion of the body part 20, thereby cooperating with the closure flaps 22a and 22b, 22b of the shell 21 to retain the outer shell upon the body part.

The embodiment typified by Figs. 7 and 8 corresponds generally to that of Figs. 1 through 6 and like parts are designated by like reference characters. The embodiment of Figs. 7 and 8 specifically illustrates the outer shell 21 of the full length of the body part when of full size and the outer shell 21 provided with one or more series

of weakened lines 21a extending peripherally thereof corresponding to the number and relative positions of the weakened lines extending peripherally of the body part, to afford corresponding severing of both the outer shell and the body part upon reduction of size. A simple procedure for attaining such reduction of size is had by sliding the outer shell 21 downwardly relative to the body part and thereafter severing the desired lower portion of the outer shell and the desired upper portion of the body part.

Fig. 9 typifies a blank for forming the body part 20 and the indicated panels and other parts of the blank are designated correspondingly as above referred to. As appears from Fig. 9, the closure flap 22c may be integral with the material of the body part, the closable bottom being provided by the panels indicated 22c. The panels 20' combine with the panels appearing topmost in Fig. 9 to form overlapping glue areas for effecting the hollow formation of the body part.

The embodiment illustrated in Figs. 10, 11, and 12 corresponds in the main to that typified by Figs. 1 through 6 and corresponding parts are designated by like reference characters. The embodiment shown in Figs. 10, 11, and 12 illustrates in particular the employment of means supplemental to the closure flaps for locking the outer shell 21 relative to the body part 20. Applicable to such arrangement and providing for reducing the body part to half size, Figs. 10, 11, and 12 illustrate two sets of locking means, an upper set when the outer slide or shell 21 is in uppermost position, and a lower set when the outer slide or shell 21 is in reduced position. The upper set of locking means comprises the locking tongue 24 carried by the shell 21 which combines with the locking aperture 25 carried by the body part 20. For locking the shell 21 at lowermost position, the locking tongue 24 coacts with the lowermost aperture 26 carried by the body part. Preferably, as shown, such sets of locking means are arranged on oppositely disposed lateral sides of the shell 21 and body part 20. Preferably, also, such locking tongues 24, 24 and locking apertures 25, 25 and 26, 26 are formed by die-cutting the material of the shell 21 and body part 20.

The blanks illustrated in Figs. 13 and 14 are typical for forming the outer shell and body part of the carton or container of integral material. The panels corresponding to the stated sub-parts of the shell 21 and body 20 bear like reference characters.

Desirably, and as shown in Figs. 10 and 13, the employment of the stated positioning-setting means for the shell 21, obviates the need of any closure flap (such as the closure flaps 22c of the respective embodiments shown in Figs. 1 through 6 and Figs. 7 through 9) for the uppermost portion of the body part 20.

From the above, it is apparent that the invention embodies a carton or container having a body part formed of sheet material and capable of being knocked-down and when set up is provided with a dispensing opening at one end, the body part desirably being weakened at predetermined locations, a foldable shell formed of sheet material and having a configuration when set up closely approximating that of the body part, the shell desirably being weakened at locations corresponding to the weakened locations of said body part or in lieu thereof having a dimension corresponding to the spacing of a weakened portion

of said body part from an end of said body part, and closure means for jointly closing the dispensing opening of said body part and for retaining said shell in fixed position relative to said body part, said shell desirably, and said shell and said body part preferably jointly, having means for locking said shell in selected position relative to said body part.

Whereas I have described my invention by reference to specific forms thereof, it will be understood that many changes and modifications may be made without departing from the spirit of the invention.

I claim:

1. A carton or container comprising a body part of sheet material having a dispensing opening at or approximate one end, said body part being otherwise closed, a flap carried by said body part adjacent its dispensing opening, said body part being weakened along a line which extends peripherally thereof intermediate of and transversely to its length to afford reduction of size, a shell formed of sheet material and embracing said body part and having a configuration closely approximating the configuration of the said body part, said shell being weakened in a manner substantially corresponding to the weakening of said body part to afford corresponding reduction of size, said shell having an open end adjacent the dispensing opening of said body part, and closure flap means carried by said shell proximate its said open end and arranged to embrace said flap of said body part for jointly closing the dispensing opening of said body part and for retaining said shell in fixed position relative to said body part.
2. A carton or container comprising a body part of sheet material having a dispensing opening at or approximate one end, said body part being otherwise closed, a flap carried by said body part adjacent its dispensing opening, said body part being weakened along a line which extends peripherally thereof intermediate of and transversely to its length to afford reduction of size, a shell formed of sheet material and embracing said body part and having a configuration closely approximating the configuration of said body part, said shell having a length corresponding to the distance intervening between said weakened line of said body part and the open end of said body part, said shell having an open end adjacent the dispensing opening of said body part, and closure flap means carried by said shell proximate its said open end and arranged to embrace said flap of said body part for jointly closing the dispensing opening of said body part and for retaining said shell in fixed position relative to said body part.
3. A carton or container comprising a body part of sheet material having a dispensing opening at or approximate one end, said body part being otherwise closed, a flap carried by said body part adjacent its dispensing opening, said body part being weakened along a line which extends peripherally thereof intermediate of and transversely to its length to afford reduction of size, a shell formed of sheet material and embracing said body part and having a configuration closely approximating the configuration of the said body part, said shell being weakened in a manner substantially corresponding to the weakening of said body part to afford corresponding reduction of size, said shell having an open end adjacent the dispensing opening of said
- 5 body part, and closure flap means carried by said shell proximate its said open end and arranged to embrace said flap of said body part for jointly closing the dispensing opening of said body part and for retaining said shell in fixed position relative to said body part, said closure flap means comprising oppositely related flaps arranged to be inwardly disposed, and a flap arranged to encompass said oppositely related flaps when in closed position and held by frictional engagement between said shell and said body part.
- 10 4. A carton or container comprising a body part of sheet material having a dispensing opening at or approximate one end, said body part being otherwise closed, said body part being weakened along a line which extends peripherally thereof intermediate of and transversely to its length to afford reduction of size, a shell formed of sheet material and embracing said body part and having a configuration closely approximating the configuration of the said body part, a flap carried by said body part proximate its dispensing opening, said shell being weakened in a manner substantially corresponding to the weakening of said body part to afford corresponding reduction of size, said shell having an open end adjacent the dispensing opening of said body part and closure flap means carried by said shell proximate its said open end and arranged to embrace said flap of said body part and cooperating with said flap of said body part for jointly closing the dispensing opening of said body part and for retaining said shell in fixed position relative to said body part, said closure flap means comprising oppositely related flaps arranged to be inwardly disposed, and a flap arranged to encompass said oppositely related flaps when in closed position and held by frictional engagement between said shell and said body part.
- 15 5. A carton or container comprising a body part of sheet material having a dispensing opening at or approximate one end, said body part being otherwise closed, said body part being weakened along a line which extends peripherally thereof intermediate of and transversely to its length to afford reduction of size, a shell formed of sheet material and having a configuration closely approximating the configuration of said body part, said shell embracing said body part and open at its end adjacent the dispensing opening of said body part, said shell having a length corresponding to the distance intervening between said weakened line of said body part and the open end of said body part, and closure flap means carried by said shell proximate the dispensing opening of said body part for jointly closing the dispensing opening of said body part and for retaining said shell in fixed position relative to said body part, said closure flap means comprising oppositely related flaps arranged to be inwardly disposed, and a flap arranged to encompass said oppositely related flaps when in closed position and held by frictional engagement between said shell and said body part.
- 20 6. A carton or container comprising a body part of sheet material having a dispensing opening at or approximate one end, said body part being otherwise closed, said body part being weakened along a line which extends peripherally thereof intermediate of and transversely to its length to afford reduction of size, a shell formed of sheet material and embracing said body part and having a configuration closely approximating the configuration of said body part, a flap carried by said body part proximate its dispensing opening

opening, said shell having a length corresponding to the distance intervening between said weakened line of said body part and the open end of said body part, said shell having an open end adjacent the dispensing opening of said body part, and closure flap means carried by said shell proximate the dispensing opening of said body part and cooperating with said flap of said body part, for jointly closing the dispensing opening of said body part and for retaining said shell in fixed position relative to said body part, said closure flap means comprising oppositely related flaps arranged to be inwardly disposed, and a flap arranged to encompass said oppositely related flaps when in closed position and held by frictional engagement between said shell and said body part.

7. A carton or container comprising a body part of sheet material having a dispensing opening at or approximate one end, said body part being otherwise closed, a shell formed of sheet material and embracing said body part and having a configuration closely approximating the configuration of said body part, said shell having an open end adjacent the dispensing opening of said body part, closure flap means carried by said shell proximate the dispensing opening of said body part for jointly closing the dispensing opening of said body part and for retaining said shell in fixed position relative to said body part, and respectively, cooperative locking means carried by said body part and shell for locking said shell in position relative to said body part.

8. A carton or container comprising a body part of sheet material having a dispensing opening at or approximate one end, said body part being weakened along a line which extends peripherally thereof intermediate of and transversely to its length to afford reduction of size, a shell formed of sheet material and embracing said body part and having a configuration closely approximating the configuration of said body part, said shell having an open end adjacent the dispensing opening of said body part and having a length corresponding to the distance intervening between said weakened line of said body part and the open end of said body part, closure flap means carried by said shell proximate the dispensing opening of said body part for jointly closing the dispensing opening of said body part and for retaining said shell in fixed position relative to said body part, and respective, cooperative locking means carried by said body part and shell for locking said shell in position relative to said body part.

9. A carton or container comprising a body part of sheet material having a dispensing opening at or approximate one end, said body part being otherwise closed, said body part being weakened along a line which extends peripherally thereof intermediate of and transversely to its length to afford reduction of size, a shell formed of sheet material and embracing said body part and having a configuration closely approximating the configuration of said body part, said shell having an open end adjacent the dispensing opening of said body part and having a length corresponding to the distance intervening between said weakened line of said body part and the open end of said body part, closure flap means carried by said shell proximate the dispensing opening of said body part for jointly closing the dis-

pensing opening of said body part and for retaining said shell in fixed position relative to said body part, and a plurality of sets of locking means jointly carried by said shell and said body part for locking said shell in selected positions relative to said body part corresponding to reduction of size of said body part.

10. A box, reducible in size and formed from sheet material, comprising a box body adapted to contain material and having a dispensing opening; a tubular, open-ended shell, fitting closely about the said box body adjacent said dispensing opening and being slidable on said box body to positions relatively more remote from said dispensing opening, that open end of said shell which lies adjacent the said dispensing opening of the box body being provided with closure means which are foldable into and out of closing position over the said dispensing opening of the box body; and releasable means for retaining said shell in position on said box body, said box body being weakened along a line which extends peripherally thereof intermediate of and transversely to its length so part of the length of said box body may be torn off for the purpose of reducing the size of the box.

11. A box, reducible in size and formed from sheet material, comprising a box body adapted to contain material and having a dispensing opening provided with closure flap structure; and a tubular, open-ended shell fitting closely about the said box body adjacent said dispensing opening and being slidable on said box body to positions relatively more remote from said dispensing opening, that open end of said shell which lies adjacent the said dispensing opening of the box body being provided with closure-supporting tabs which are folded inwardly and lie under the said closure flap structure of said box body, supporting the same, said open end of said shell being provided, further, with closure flap structure which tucks in between said shell and said box body and retains the closure flap structure of said box body in place as well as securing said shell in position on said box body, said box body being weakened along a line which extends peripherally thereof intermediate of and transversely to its length so part of the length of said box body may be torn off for the purpose of reducing the size of the box.

12. A box, reducible in size and formed from sheet material, comprising a box body adapted to contain material and having a dispensing opening; a tubular, open-ended shell, fitting closely about the said box body adjacent said dispensing opening and being slidable on said box body to positions relatively more remote from said dispensing opening, that open end of said shell which lies adjacent the said dispensing opening of the box body being provided with closure means which are foldable into and out of closing position over the said dispensing opening of the box body; and respective cooperative locking means carried by said box body and said shell for retaining said shell in position on said box body, said box body being weakened along a line which extends peripherally thereof intermediate of and transversely to its length so part of the length of said box body may be torn off for the purpose of reducing the size of the box.

WILLIAM A. RINGLER.
